UNITED STATES PATENT OFFICE.

JACOB WEST, OF BOLIVAR, PENNSYLVANIA.

STEAM-ENGINE.

SPECIFICATION forming part of Letters Patent No. 399,101, dated March 5, 1889.

Application filed November 17, 1888. Serial No. 291,110. (No model.)

To all whom it may concern:

Be it known that I, JACOB WEST, a citizen of the United States of America, residing at Bolivar, in the county of Westmoreland and State 5 of Pennsylvania, have invented certain new and useful Improvements in Steam-Engines; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to an improvement in steam-engines.

My invention consists of a cone-shaped cylinder in which is fitted a conical spirally-grooved piston arranged in such manner that 20 by means of one, two, or more feed-pipes the steam is admitted into the cylinder at the larger end and comes in contact with the grooves of the piston, causing it to revolve at a very high rate of speed, and escapes at the 25 smaller end.

I have shown my preferred form of construction in the accompanying drawings, wherein like letters of reference are used to designate similar parts in the several views, and in 30 which—

Figure 1 is a side elevation. Fig. 2 is a longitudinal vertical section of the same. Fig. 3 is a transverse vertical section on the line $\alpha\alpha$ of Fig. 2.

35 A indicates the outer cylinder, the major part of which is conical. The outer surface of the head A' thereof is circular, and has a flange, A², and a steam connecting branch or feed-opening, a. To the flange A² a head, B, 40 is bolted. The feed-opening a communicates with an internal circular steam-passage, a', which has one or more ports, a², opening therefrom into the interior of said outer cylinder or casing.

45 The smaller end of the cylinder A has an egress-port, a³, to which a suitable pipe may be attached to convey the exhaust-steam away from the cylinder. The inner chamber of said cylinder is of regular conical form, and 50 a conical piston, C, is fitted therein, having shaft-extensions c and c' from each end there-

of, upon which a power-transmitting pulley, C', is keyed. The two shaft-extensions have bearing in the ends of the outer cylinder, being surrounded by suitable packings or having stuffing-boxes.

The conical piston C is constructed with a series of spiral grooves, c², which provide flanges or wings against which steam impinges. The large end of the piston has a 60 plain surface, C³, which affords a stable base for the grooves, and at the same time does not deteriorate from the desired action of the piston, as said surface is in rear of the ingress port or ports a². The piston is shorter than 65 the interior chamber of the cylinder A, thereby leaving a space between the end of the said piston and the inner surface of the end wall of the cylinder, thus providing a chamber under the egress-port a³. The said piston snugly fits within the cylinder, having only sufficient space to allow it to have un retarded movement. The steam entering the ingress port or ports flows into the spiral grooves of the piston and against the projections formed by said grooves. This force revolves said piston and the transmitting-pulley. The steam follows the grooves or exerts its pressure on the piston until the whole length of the said piston is traversed thereby, 70 or until it reaches the end space between the reduced part thereof and of the cylinder and escapes. By this means a continuous revolution is sustained.

Having thus described my invention, what I 75 claim as new, and desire to secure by Letters Patent, is—

1. The combination, substantially as described, of the cylinder or casing having a conical chamber, lateral ingress and egress 80 ports communicating, respectively, with the larger and smaller ends of said chamber, a head to close the larger end of said chamber, and a conical piston provided with spiral grooves terminating near the larger end of the piston. 95

2. The combination, substantially as described, of a cylinder or casing provided with a conical chamber, an ejection-port opening laterally from the smaller end of the chamber, a circular steam-passage surrounding the 100 larger end of the chamber and communicating therewith through one or more radial openings,

an ingress-port opening into said circular chamber, a removable head to close the larger end of the chamber, and a conical spirally-grooved piston mounted in the chamber with
5 its shaft journaled in the heads of the cylinder and provided at its larger end beyond the ingress-ports with a peripheral plain surface.

In testimony whereof I affix my signature in presence of two witnesses.

JACOB WEST.
